PROJECTILE FUSE

Lyle K. Liljegren, Silver Spring, Md.

Application May 22, 1945, Serial No. 595,230

14 Claims. (Cl. 102—81.2)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to an improved delay arming projectile fuze, and more particularly to a fuze for use with nonrotating type projectiles.

It is a primary object of this invention to provide a fuze for nonrotating type projectiles which will remain in a safe or disarmed condition during the initial stage of its flight and which will arm only after the fuze and the projectile, in which it is contained, has traveled a sufficiently distance from the weapon from which it is fired, so that detonation of the fuze would not endanger the gun crew.

Another object of the invention is to provide a fuze which is actuated, for arming the fuze, by means incident to the flight thereof so that if the projectile, in the initial part of its flight, should strike a mask or a tree, burst of the shell would not result.

More particularly, it is an object of the invention to provide a detonator carrier which is spring urged, selectively, for aligning either of two or more detonators with a flash passage, and which is so constructed that a portion of the flash passage will initially function to retain the detonator carrier in an intermediate, safe position.

Still a further aim of the invention is to provide a fuze having a firing pin which is rotatably connected to an arming vane and connected by spring means to a portion of the flash passage, so that upon being actuated by the arming vane, it will function for retracting said portion of the flash passage into a position to permit arming of the fuze.

Other objects and advantages of the invention will hereinafter become more fully apparent from the following description of the drawings, which illustrates preferred embodiments thereof, and wherein:

Figure 1 is a longitudinal, substantially central sectional view, of a fuze constructed in accordance with the invention;

Figures 2, 3, and 4 are cross sectional views of the fuze taken substantially along planes as indicated by the lines 2—2, 3—3, and 4—4, respectively, of Figure 1;

Figure 5 is a view similar to Figure 4 showing the fuze carrier in an armed position;

Figure 6 is a cross sectional view of the fuze, on an enlarged scale, taken substantially along a plane as indicated by the line 6—6 of Figure 1;

2

Figure 7 is a plan view of the detonator carrier or rotor, shown detached.

Figures 8 and 9 are transverse sectional views taken substantially along the planes of the lines 8—8 and 9—9, respectively of Figure 7;

Figure 10 is a fragmentary side elevational view of the upper portion of the fuze housing;

Figure 11 is a side elevational view of one element of the fuze; and

Figure 12 is an end view in elevation thereof.

Referring more particularly to the drawings, wherein like reference characters designate like or corresponding parts throughout the several views, 15 designates generally the improved fuze in its entirety and which includes a housing, designated generally 16, the forward end of which, prior to firing, is inclosed within a removable cup-shaped cover 17.

The housing 16, adjacent its rear end, is provided with an externally threaded portion 18 which is adapted to threadedly engage in the nose of a nonrotating type projectile, not shown, such as a mortar shell, for detachably mounting the fuze 15 on the forward end thereof. Rearwardly of the threaded portion 18, the housing 16 is provided with a rearwardly opening chamber 19 which has a threaded rear end in which is detachably mounted a cup-shaped booster charge 21. The inner wall of the booster charge 21 is provided with a central opening 22 which is normally closed by cup-shaped member 23 which contains a small quantity of a relatively sensitive explosive.

The housing 16 is provided with an axially disposed bore 24 which opens outwardly of the threaded nipple 25, at the forward end thereof, and which is provided with a restricted rear end which opens into the inner part of the chamber 19. A tube or sleeve 26 is mounted in the bore 24 and extends from the forward end thereof to

adjacent its rear end and seats, at its rear end, on an annular step or shoulder 27 of the bore 24. The rear end of the sleeve 26 is internally threaded at 28 to engage a threaded portion 29 of a sleeve or flash tube 30 which is disposed therewithin.

The threaded portion 29 is likewise disposed at the rear end of the sleeve 30. The sleeve 30, at its rear end, is provided with an integral hollow stem 31 which projects through the restricted 50 rear end of the bore 24 and into the chamber 19. The inner end of the stem 31 is counterbored to receive a primer 32 which opens into the interior of the sleeve 30. As seen in Figure 1, the rear end of the sleeve 30 normally seats on the annular shoulder 33 formed by the restricted portion of

the bore 24 to limit the extent to which the stem extends into the chamber 19, so that when the sleeve 30 is in its rearmost position, as seen in Figure 1, the rear end of the stem 31 terminates in spaced relationship to the cup 23, with which it is in alignment. The outer sleeve 26 is provided with an elongated opening 34 and the inner sleeve 30 is provided with a plurality of openings 35 which are spaced circumferentially and longitudinally thereof.

A cap 36 is provided with an internally threaded recess 37 for engaging the nipple 25 and forms the detachable forward end of the housing 16 and is provided with a forwardly extending centrally disposed nipple 38 which has a bore 39 extending therethrough and opening into the recess of the cap 36. The bore 39 forms a bearing for a shaft 40 which is rotatably disposed therein and which is provided with a threaded forward end 41 which is engaged by a threaded hub 42 of an arming vane 43. A helical spring 44 surrounds a portion of the shaft 40 and the nipple 38 and is disposed between the cap 36 and a collar 45. The collar 45 and a flange of the hub 42 form races for anti-friction bearings 46 to mount the arming vane 43 for relatively free rotation relatively to the spring 44. The rear end of the shaft 40 is disposed within the sleeve 26 and is enlarged to form an annular forwardly facing shoulder 47 which bears against a washer or collar 48 which is mounted on the restricted portion of the shaft 40. The rear end of the enlarged portion of the shaft 40 extends into the forward end of the sleeve 30 and terminates in a restricted tapered projection firing pin 49 which is axially disposed in alignment with the primer 32. Between the sleeve 30 and the collar 48, a helical spring 50 is disposed around the enlarged portion of the shaft 40 and has its forward end anchored in a recess in said shaft and its rear end anchored in the sleeve 30.

The forward portion of the cap 36 is provided with a transverse bore 51 which registers with a transverse opening 52 in one position of the shaft 40, for receiving a cotter pin 53 having a ring 54 connected to the eye thereof. The cotter pin 53 forms a safety pin to hold the shaft 40 against sliding or rotary movement.

The housing 16 is provided with a bore 55 which is disposed off center thereof and which extends longitudinally of the housing. The rear end of bore 55 is counterbored and opens into the chamber 19 and the forward end thereof opens into a portion of the annular shoulder of the housing 16 which surrounds the nipple 25, and said forward end contains a bushing 56. The inner wall of the booster 21 is spaced from the inner end of the chamber 19 to form a substantially circular closed chamber which contains a rotor or detonator carrier 57. The carrier 57, which is best illustrated in Figures 7 and 8, is provided with a tapered end from the upper surface of which extends an integral sleeve or spindle 58 which is journaled in the counterbored rear end of bore 55 to swingably mount the rotor 57 in the chamber 19. As seen in Figures 7 and 8, the rotor 57 is provided with two bores 59 and 60 which extend therethrough from the front to the rear sides thereof. The bore 59 contains a super quick detonator 61 and the bore 60 contains a delay detonator 62. The bores 59 and 60 are equidistant radially from the spindle 58 and are circumferentially spaced from one another. The carrier 57 is also provided with a depression or well 63 which is disposed in the enlarged end

thereof, between the bores 59 and 60 and which opens outwardly of said end and which is also disposed in axial alignment with the spindle 58 and with a bore 64, which is located therebetween. Well 63 opens outwardly of the upper or forward surface of the rotor 57 and extends to adjacent the bottom or rear surface thereof, as best seen in Figures 1 and 8. As seen in Figure 1, the lower end of the bore 64 is threaded to receive a closure 65 which forms a seat for an expansion spring 66, the upper end of which bears against a plunger 67. The plunger 67 has a forwardly extending stem which is reciprocally disposed in the restricted forward end of the bore 64 and which projects therefrom and normally bears against the inner end of chamber 19. Said inner end of chamber 19 is provided with circumferentially spaced indentations, one of which is shown in dotted lines in Figure 1 at 68, for selectively receiving the stem of the plunger 67 when the rotor 57 is moved to an armed position, as will hereinafter be described.

A continuation of the bore of spindle 58 extends part way through the body of the rotor 57 and the rear end thereof opens into a transversely disposed slot 69, formed in the bottom part of the rotor 57. A torsional spring, designated generally 70, comprises an elongated strand of resilient wire having a free end turned back upon itself to form a hook 71. The strand of wire of the spring 70 extends through the bore 55 and the bore of the spindle 58 and has its hook portion 71 extending into and in engagement with the slot 69, the width of which is only slightly greater than the diameter of the wire, for keying the spring 70 to the rotor 57. The opposite end of said strand of wire extends through and is journaled in the bushing 56 and terminates in the slot 72 formed in the forwardly facing shoulder which surrounds the nipple 25. As an alternative, the bushing 56 can be fixed to the spring 70 and rotatably disposed in the bore 55. Said end of the strand of wire is suitably secured to a lever arm 73 which projects laterally therefrom and the free end of which is spring biased toward said strand. As seen in Figure 10, the ends of the slot 72 are indented to receive and engage the resilient free end of the lever arm 73 for latching said arm either in the position, as seen in Figure 10, or in a position in which the arm 73 is disposed at an angle of 180° to its position of Figure 10.

The cover 17, which incloses the arming vane 43, the lever arm 73 and the safety pin 53, is removably held in position on the housing 16 by a removable band of adhesive tape 14. Cover 17 protects the aforementioned parts during storage and transportation and is removed prior to preparing the fuze 15 for firing.

Assuming that the cover 17 has been removed and that the rotor 57 is in its intermediate or disarmed position of Figures 1 and 4, the housing 16 is threaded into the forward end of a projectile and connected thereto by a threaded portion 18. To prepare the fuze 15 for firing, the arm 73 is swung from an intermediate position, midway of the ends of the slots 72, in either direction. If it is desired to produce a super quick functioning of the fuze upon impact, the lever arm 73 is swung to the left or clockwise and engaged in the indentation marked SQ, as seen in Figure 10, or if delay functioning of the fuze upon impact is desired, the lever arm is swung to the right or counterclockwise and engaged in the other indentation marked D. Either

movement of the lever arm 73 will produce a 90° torque on the resilient wire strand and, assuming that the lever arm 73 is in its position of Figure 10, it will urge the carrier 57 to swing in a clockwise direction from its position of Figure 4. However, the stem 31 extends into the well 63 to prevent angular movement of the rotor 57 about the axis defined by its spindle 58. The fuze 15 is now ready to function except for removal of the safety pin 53 which is accomplished just previous to insertion of the projectile, containing the fuze, into the mortar tube. Assuming the projectile containing the fuze has been fired and is in flight, the vanes 43 are pitched so that on acceleration of the fuze 15 the arming vane 43 will rotate in a counterclockwise direction. This will tension the spring 50 to pull the sleeve 30 toward the forward end of the fuze 15 thereby moving the threaded portion 29 forwardly and into engagement with the threaded portion 28. The torque of the spring 50 will exert a torsional strain on the sleeve 30 to rotate it counterclockwise, looking from front to rear of the fuze 15, to thereby screw the sleeve 30 through the threaded sleeve portion 28 and retract the stem 31 forwardly and away from the well 63, in which it is disposed. As the stem 31 moves out of engagement with the well 63 the rotor 57 is released so that the torque exerted thereon by the spring 70 will swing the rotor 57 in a clockwise direction from its position of Figure 4 to move the super quick detonator 61 into alignment with the bore of the spindle or sleeve 31. As the rotor 57 reaches this position, the forward end of the plunger 67 will be received in one of the indentations 68 for latching the rotor in an armed position. After the threaded portion 29 has moved entirely through the threaded portion 28 the sleeve 30 is released and is free to revolve with the shaft 49 and the primer 32 is disposed adjacent to but still spaced from the tapered projection 49. The springs 44 and 50 both function, with the parts thus disposed, as creep springs to prevent the primer 32 and projection 49 for moving toward one another. Upon impact of the arming vane 43 with a target, the shaft 49 is driven rearwardly against the tension of springs 44 and 50 to cause projection 49 to strike and detonate the primer 32. The flash therefrom passes through the bore of the stem 31 to ignite the detonator 61 which instantaneously ignites the explosive in the cup 23 for detonating the booster 21 and the burster charge, not shown, of the projectile. Should the fuze graze the target, inertia will carry the sleeve 30 forward in the sleeve 26 and against the springs 44 and 50 to detonate the primer 32 by engagement with projection 49.

It will likewise be readily obvious that if the lever arm 73 is moved to engagement with the indentation designated D, that upon retraction of the spindle 31 out of engagement with the carrier 57, the carrier will be swung in a counterclockwise direction by the oppositely exerted torque of the spring 70 to move the delay detonator 62 into alignment with the bore of spindle 31 and into the position, as seen in Figure 5. The delay detonator 62 includes a charge of black powder which produces a delay ignition of the charge contained in the cup 23 to permit penetration of a target before detonation of the projectile.

As clearly illustrated in Figure 1, the initial position of the threaded portion 29 is to the rear of and out of engagement with the threaded por-

tion 28 to permit free rotation of the sleeve 30 in an opposite or clockwise direction so that if propelling gases escaping from the muzzle of the tube, from which the projectile is fired, stream past the shell and cause the arming vane to rotate in a clockwise direction, the torque thus produced cannot screw the sleeve 30 into a tight engagement with the sleeve 26 which would prevent the sleeve 30 from thereafter being turned 10 in the opposite direction and advance forwardly through the threaded portion 28, and thus prevent arming of the fuze while in flight. Thus by the means just described the arming vane is allowed to spin free in a backward direction due 15 to the threaded portions 28 and 29 being initially assembled in a disengaged condition.

Various modifications and changes are contemplated and may obviously be resorted to, without departing from the spirit and scope of the invention as hereinafter defined by the appended claims, as only a preferred embodiment thereof has been disclosed.

I claim:

1. A fuze for nonrotatable type projectiles comprising a housing, a detonator carrier mounted to oscillate therein, a torsional member engaging said carrier and projecting from said housing, means to set the torsional member for biasing the carrier in either of two directions from a central position, arcuately spaced detonating means contained in the carrier, means engaging the carrier for initially holding it in a central position, said means being movable out of engagement with the carrier during flight of the fuze, and said fuze 30 having a flash passage into alignment with which one of the detonating means is selectively moved by the torsional member, when the carrier engaging means is retracted out of engagement with the carrier.
2. A fuze as in claim 1, and an arming vane connected to the carrier engaging means for moving said means out of contact with the carrier during flight of the projectile.
3. A fuze as in claim 1, said torsional member comprising a strand of resilient wire rotatably disposed in the housing and having one end keyed to the carrier, a lever arm projecting laterally from the opposite end of the strand and from the housing, and said housing having a slot in which said lever arm is movable, said slot having keepers at the ends thereof for releasably engaging the lever arm whereby a torsional stress in either direction can be applied to the wire strand.
4. A fuze for nonrotating projectiles comprising a housing, a firing pin slidably disposed in the housing, a primer holder containing a primer mounted for movement lengthwise relatively to the housing and firing pin, a detonator carrier mounted to oscillate in the housing and containing arcuately spaced detonators, said primer holder being initially disposed within the carrier to retain the same in a central disarmed position, adjustable spring means for resiliently biasing the carrier for selective movement to position either of the detonators in alignment with the primer after said holder is disengaged from said carrier, an arming vane connected to the firing pin for rotating the firing pin during flight of the fuze, and spring means connecting the firing pin and holder for retracting the holder out of engagement with the carrier when the firing pin is revolved.
5. A fuze for non-rotating type projectiles, comprising a housing, a detonator rotor arranged to oscillate therein between a first and second

position, said rotor having arcuately spaced detonators contained therein, means holding the rotor in a central position, said means being movable out of engagement with the rotor in response to flight of the fuze, spring means adjustable to resiliently bias said rotor for selective movement in respectively opposite directions toward either said first or said second position for moving a pre-selected one of said detonators into firing position after said rotor is released by said rotor holding means, said rotor holding means comprising a sleeve, a primer disposed in a portion of said sleeve, a shaft journaled in the housing and having one end projecting therefrom, an arming vane keyed to said end for rotating the shaft when the fuze is in flight, the opposite end of the shaft being loosely disposed in the sleeve and in alignment with the primer, a helical spring wound around the shaft and connected at one end to the shaft and at its opposite end to the sleeve, said sleeve being in threaded engagement with the housing whereby when the arming vane and shaft are revolved the helical spring will exert a torsional stress on the sleeve to rotate it and thereby retract it relatively to the rotor, and said shaft being reciprocably mounted in the housing to engage and detonate the primer upon impact of the fuze.

6. In a fuze, a housing having a chamber, a rotor in said chamber pivotable in both directions about an axis fixed with respect to said housing, a spring secured to said rotor, means manually adjustable to stress said spring in either direction to urge said rotor in a corresponding direction, a bore in said housing offset from said axis and opening into said chamber, a sleeve movable axially in said bore from a first to a second position, said sleeve when in said first position engaging and holding said rotor in a central unarmed position and when moved to second position freeing said rotor, and first and second detonators carried by said rotor each said detonator being moved by said rotor into alignment with said sleeve for respective directions of pivoting of said rotor.

7. In a fuze as recited in claim 6, and second means operable in response to movement of said fuze in flight to move said sleeve from first to second position.

8. In a fuze as recited in claim 7, said second means comprising a shaft journaled in said housing coaxially of said sleeve and having a portion extending exteriorly of said housing, a vane on said extending portion, and a coil spring wound about said shaft and having one end anchored thereto and its other end fixed to said sleeve.

9. In a fuze as recited in claim 8, there being a threaded connection between said sleeve and said housing whereby said sleeve on rotation is moved to second position.

10. In a fuze, a housing having a central bore, a sleeve in said bore, there being a screw threaded connection between said sleeve and housing whereby on rotation, said sleeve is moved axially of said bore from a first to a second position, arming means engaged and held by said sleeve in unarmed position when said sleeve is in first position, a shaft journaled in said housing in axial alignment with said sleeve, vane means for rotating said shaft in response to flight of said fuze, and a coil spring surrounding said shaft and connected at its one end to said shaft and at its other end to said sleeve.

11. A fuze as recited in claim 10, a tube fixed in said housing, said sleeve fitting said tube and having threads adapted to engage threads of said tube, said threads being normally disengaged, said spring when tensioned by turning of said shaft drawing said sleeve axially relatively to said tube to positively engage said threads.

12. For use in a non-rotating type projectile, a fuze comprising a housing having a bore and a chamber communicating with one end of the bore, a firing pin slidable in the bore, a rotor pivoted in said chamber on an axis parallel with and offset from the axis of said bore and pivotable about said offset axis in both directions of rotation, said rotor having first and second detonators therein, each said detonator being moved into coacting relation with said firing pin when said rotor is rotated in a respective one of said directions from a central position, a normally unstressed spring connected with said rotor, means connected with said spring and manually adjustable to stress said spring to urge said rotor into a selected direction of rotation, and means to maintain said spring in manually stressed condition.

13. In a fuze for a projectile, a housing, an arming device in said housing and movable from a first unarmed position to a second armed position, a tube fixed in said housing, a sleeve mounted for movement axially along said tube and having a portion normally engaging and holding said arming device in first position, a rotatable shaft, means for rotating said shaft in response to passage of said projectile in flight, spring means connecting said shaft and sleeve, there being normally uncoupled threads between said tube and sleeve, said sleeve being moved axially by said spring means in response to initial rotation of said shaft to bring said threads into threading engagement, further rotation of said sleeve through said spring means moving said sleeve axially along said tube out of contact with said arming device to free said device for movement to second position.

14. In a fuze, a housing, a chamber in said housing, a rotor pivotable in said chamber in both directions about an axis in fixed relation with said housing, a normally unstressed spring attached to said rotor, adjusting means carried by said housing and connected with said spring to stress the same to thereby urge said rotor in either one of two opposite directions of rotation, means to hold said spring in stressed condition, first and second detonators of different time characteristics carried by said rotor, either of said detonators being moved with said rotor into armed position when said rotor is released for pivotal movement by said spring in a respective direction, means normally locking said rotor in central unarmed position, and means responsive to flight of a projectile carrying said fuze to move said locking means to free said rotor for movement under urge of said spring when stressed.

LYLE K. LILJEGREN.
